[57] ABSTRACT

The apparatus comprises a tubular member which is telescopically insertable over a standard terminal screw and which has a length such that it will extend down to the terminal on which the screw is mounted and still enclose the head of the screw when the screw is fully retracted or withdrawn. The tubular member is provided at its outer end with a projecting tongue for wrapping the end of a wire around the threaded screw post as the tubular member is turned. The tongue is preferably inclined toward the axial center of the tubular member and sharpened along its leading side edge in the direction of turn of the tubular member to enable it to bite into the wire and hold it while the tubular member is turned. A wire containing tubular cup or ring may initially be mounted on the terminal to facilitate the wire wrapping operation of the tubular member. The tubular member may be constructed to coact with a screwdriver to fasten the wrapped wire end.

APPARATUS FOR WRAPPING SCREW-TYPE ELECTRICAL TERMINALS

THE INVENTION

This invention relates to apparatus for wrapping the ends of electrical wire connectors around standard screw type terminals provided in electrical devices.

Electrical connectors of the type indicated comprise a screw threaded into the terminal of an electrical or other device and having a head of sufficient diameter to cover a conductor or wire end looped or wrapped about the threaded shank of the screw. Solid wire connectors often have loops performed in the wires thereof before they are mounted on the terminals. If this is done manually by a screwdriver or a pair of pliers, this is at best an awkward operation, and so much so, that many electricians in an attempt to make it easier, will strip off several inches of the conductor insulation covering and use the end of the conductor as a tool to wrap the bare wire around the screw. This however, results in a waste of the conductor material and does not provide a very good terminal connection. Further, it cannot be followed in wiring many electronic devices and small machines in which the terminals are of necessity located in relatively difficult positions for applying connectors, as for example in deep cavities in a machine, or fixture, or even in an electric clock. In such situations, the worker may partially preform a loop in the wire end before placing it around the terminal screw, and then attempt to pull it around the screw with a tool, but he is seldom able by this method to get a good 360° wrap of the wire around the screw. It is not unusual also, that wire ends which are partially or fully performed into loops, are mounted on the terminals in the wrong way so that as the terminal screws are tightened, the loops tend to unwind. Frequently, however, such solid wire connectors, as well as all stranded conductors, are wrapped around the terminal screw shanks using a screwdriver or a pair of pliers, or manually. In such practice of what is probably the most common method the stranded conductor provides a special problem, because when the bunched wires on the exposed end of such a conductor is applied around a terminal screw, they have a tendency to extrude or flow out from under the screw head as the screw is tightened down on the terminal. This results in both a poor electrical connection and a poor mechanical connection. Such a connection will not conduct the full flow capacity of the conductor, and it can be pulled loose from the terminal rather easily. It has been found that it is not unusual for as much as 50 percent of the strands to be out from under the terminal screw head unless the connection is very carefully made. This constitutes a real hazard for the exposed wire strands in the usage of the device can be spread out and frayed and come into contact with the strands of an adjacent terminal of the device to cause a short. Also where conditions of vibration exist in the usage of the device, a connection of this type will easily loosen up and become disconnected. The art has attempted to overcome this problem, by providing a lug having an opening into which the bunched strands are pushed and then clamping the inserted strands by various means. This method however, has not proved completely satisfactory, for in many instances in which it has been practiced, as in those situations where such compression type terminations are not used, the tightening of the terminal screws

will cause the portions of the bunched strands around such screws to be partially extruded and often broken to provide a weak connection that is hazardous in use. The art has also attempted to solve the problem by other methods, such as by making the screw heads larger and larger and using solder, but so far as I am aware no simple, inexpensive solution to the problem has as yet been devised by those skilled therein.

The primary purpose of my invention is to provide a simple, inexpensive apparatus capable of quickly and readily wrapping both solid and stranded conductor ends around terminal screws so as to effect a perfect, strong electrical connection.

For a fuller understanding of the nature and objects 15 of my invention, as well as the advantages and novel features thereof, reference is made to the following detailed description which should be read in conjunction with the accompanying drawings, in which

FIG. 1 is a side elevation of an apparatus embodying 20 the invention;

FIG. 2 is a side elevation of the body portion of the device shown in FIG. 1, partly in section, the detachable working end part of the device being shown in dotted outline, and such figure illustrating the manner in 25 which a screwdriver may be used therewith;

FIG. 3 is an end elevation of the outer end of the detachable working end part;

FIG. 4 is an end elevation of the inner attached end 30 of such working end part;

FIG. 5 is a side elevation of the detachable working end part, partly in section, said part constituting a small size in a set thereof;

FIG. 6 is a view similar to FIG. 5 of a larger size of 35 working end part in such set;

FIG. 7 is a view, in plan, showing the manner in which the working end part coacts with a terminal screw in wrapping a wire end about the threaded shank of such screw, the working end part being shown in section taken along the line 7—7 of FIG. 8;

FIG. 8 is a vertical view, partly in vertical section, of the parts shown in FIG. 7, and additionally showing the terminal in vertical section, the lower end of the body portion of the device to which the working end part is attached, and the lower end of a screwdriver extending 40 through such body portion;

FIG. 9 is a view similar to FIG. 8 showing the apparatus illustrated in the latter figure coacting with a wire containing tubular cup to wrap a stranded wire around the terminal screw;

FIGS. 10—14 are perspective views showing different forms of wire containing tubular cups or rings that may be utilized in coaction with the working end of the device shown in FIGS. 1 and 2 to wrap wire ends about 45 terminal screws; and

FIG. 15 is a sectional view showing how a screwdriver may be made an integral part of the tool.

Referring now more particularly to FIGS. 1 and 2 of the drawings, it should be first pointed out that the basic essential features of the apparatus of this invention relate to a tubular member 10, a tongue 11 integral with and projecting from the outer end of the tubular member 10, a tool shank 12 to which the tubular member 10 is connected, and a handle 13 mounted on the shank 12. It will be understood that the tubular member 10 may be integral with and form the outer end part of the tubular shank 12 and that the shank 12 may be a solid rod of any suitable cross-sectional configura-

tion. In the construction illustrated in FIGS. 1 and 2 of the drawings, the tubular member 10 and its associated tongue 11 form the outer portion of a working end part which is generally designated 14. The end part 14 may form part of a set of such parts whose sizes are dependent on the sizes of the terminal screws that are usually encountered in electrical devices. Thus, for example, I have found that a set of six end parts having tubular members 10 with interior diameters ranging from approximately three-eighths inch to one-half inch will take care of most sizes of terminal screws used in electrical devices or on machines. In the smaller sizes the end part 14 may have a general configuration somewhat like that shown in FIGS. 1-5 of the drawings, while in the larger sizes such parts may have a general configuration such as shown in FIG. 6 of the drawings.

As is shown in FIGS. 1-6, each end part 14 is composed of an outer tubular member 10, a tongue 11 and an inner attachment member 15, all integrally formed from a single piece of suitable material such as tool steel. The tubular member 10 has an interior cylindrical surface 16 which is of uniform size throughout its length. The interior diameter of the tubular member 10 approximates that of the head 20, in FIGS. 7 and 8, of the terminal screw with which it is to be used and is only sufficiently greater than the screw head diameter to permit the screw head to move freely in such member as it is advanced or retracted without there being much space therebetween. The tubular member 10 should have a length such that when the tongue 11 is in contact with the terminal 21, in FIG. 8, on which the screw is mounted, such member 10 will rise above the screw head 20 in the fully retracted position on the terminal screw, as is illustrated in FIG. 8.

The inner attachment member or portion 15 of end part 14, has a length approximating that of the outer tubular member or portion 10 thereof and is provided with a socket 22 that is square-shaped in cross-section and which is terminated at its inner end by shoulders 23 that function as stops for the shank 12. The socket 22 receives the outer squared end portion 24 of the shank 12 which may be provided with a spring pressed bearing 25 to assure that the end part 14 will be retained in assembled position on the shank during the handling of the tool. The other end of the shank 12 has mounted thereon a handle 13 of any suitable configuration and made of wood or plastic or any other suitable material. As is shown more clearly in FIG. 2 of the drawings, the shank 12 is preferably made of a piece of metal tubing which extends throughout the length of the handle 13 and is secured to the ends of the latter in any suitable manner. The bore 26 of the shank 12 which extends throughout the length thereof, including the end portion 24 of such shank, and which is of uniform cross-sectional area throughout its length, has a diameter approximately the same as the interior diameter of the tubular member 10 which is the smallest end part 14 in the set of such parts. Extendable through the shank 12 and through the tubular members 10 of the set of end parts is the shank of a screwdriver 28, as is illustrated in FIG. 2.

It will be understood from the foregoing discussion of the construction of the tool, that in the use thereof, the bared wire end 30 of a conductor 31 is initially laid on the terminal 21 against the left hand side of the threaded shank 32 of the terminal screw, as is shown in FIG. 7 of the drawings. As indicated the length of the

bared wire end 30 used should be greater than that of the chord bounding the segment of the tubular member 10 it will define so that when the tubular member 10 is inserted over the top of the screw the tongue 11 can engage the same a short distance from the terminal end of such wire. As indicated, this engagement of the tongue and wire will also be on the left hand side of the latter. While pressing down on the handle 13 of the tool to maintain the tongue 11 in engagement with the top surface of the terminal 21, the handle is turned in a clockwise direction, as viewed in FIG. 7, to bend the bared wire end 30 around the screw shank 32. As is shown more clearly in FIGS. 5 and 6 of the drawings, the tongue 11 is preferably inclined inwardly toward the longitudinal axis of the tubular member 10 so that in such turning movement of such member, the inclined tongue will tend to sweep the wire closely around the screw shank 32 and under the head 20 of the screw, as indicated in dotted outline in FIG. 7. It will be noted also, that during this turning movement of the tubular element 10, the screw head 20 will function as a guide to maintain such element properly centered with respect to the screw shank and thereby provide a uniform bending force on the wire. In the case of solid wire conductors, it is preferred also that the advancing or leading side edge 33 of the tongue 11 be sharpened so that it will bite into the wire and become locked there-with. It has been found that the end of a solid wire need only extend one-sixteenth of an inch beyond the leading edge 33 of the tongue when such leading edge is so sharpened. This method of locking the tongue to the wire prevents waste and enables the formation of different types of eyelets or loops on the wire. It has also been found that in the formation of such a loop in a solid wire, the tongue 11, as the tubular member 10 is turned, actually pulls the wire around underneath the screw head 20. During this operation also, the operator should preferably grasp the body of the wire and releasably hold it back as the tubular member 40 is being turned so that the bare wire end is held against the screw shank 32. By turning the tubular element 10 through a range of from 180° to 360°, and/or by varying the position at which the tongue 11 takes hold of the wire, varying different forms of eyelets or loops can be made in the wire to obtain any type of termination desired. With stranded types of wires, the sharpened edge 33 is not as important as the inclination of the tongue 11, because the sharpened edge will not affect such a secure hold on the wire strands. Thus, with stranded types of wires it is preferred to project them initially a greater distance beyond the tongue, as indicated in FIG. 8, and depend more on the inclined tongue wiping the strand ends around under the screw head and against the screw shank.

When a bared wire end, whether of a solid or stranded wire conductor, is properly wrapped around the screw shank and under the head thereof, the operator while maintaining pressure on the tool to hold the wrapped wire in position beneath the screw head, inserts the screwdriver through the bores of the tool shank 12 and the tubular element 10, and into the slot in the screw head as illustrated in FIG. 8 of the drawings. The screwdriver is then turned to tighten the screw head down on the wrapped wire end and secure the latter in place. As a result of these operations a neat, physically strong, secure and good electrical connection is made.

While it has been found that a good electrical connection will be made in the manner aforesaid, a better termination is possible in the case of stranded wires with the aid of a wire containing cap used in the manner indicated in FIG. 9 of the drawings. This result is attained because such a cup will actually hold the wire strands in place underneath the terminal screw head so that when the screw is tightened, the stranded wires can be compressed tightly without the possibility of their extruding out from under the screw head. Cups of the type that I have found suitable for the purposes of the invention are shown in FIGS. 10-14 of the drawings; the cup shown in FIG. 10 being similar to the cup generally designated 35 in FIG. 9. It will be noted that all of the cups illustrated are straight sided and of substantially uniform interior diameter throughout at least that upper depth portion thereof through which the head of the screw advances in compressing the strands tightly against the bottom wall of the cup. Below such upper depth portion of the cup, the interior wall thereof may be gradually reduced in diameter to provide a slightly rounded configuration at the lower end of the cup. The interior diameters of these cups in such upper depth portions thereof, of course, depend on size of the screw heads with which they are to be used and are such that they form a fairly close fit with such heads. This has been found to be important for if the interior diameter of a cup is appreciably greater than the screw head with which it is to be used, there is the likelihood that some of the strands may come out through the resulting space therebetween and the full confining action of the cup will be lost with a resultant weakened termination. Another factor that is important is that the cup should be deeper than the length of the tongue 11 provided on the associated tubular member and deep enough to completely encase the strands of the wrapped wire end when the screw head is advanced for tightened so that it is located below the upper edge of the cup. It has been found that desirable dimensions for these parts are a depth of approximately $7/32 - 1/4$ inch for the cup and a length of approximately one-eighth inch for the tongue will provide satisfactory wrapping results. Throughout the one-eighth inch depth of the upper portion of the cup, the interior diameter of the cup will be substantially uniform and only slightly greater than the outside diameter of the screw head. The interior diameter of such upper portion should also be at least as great as the interior diameter of the tubular member 10 which shall be used to wrap the strands within the cup so that the inclined tongue 11 provided on such tubular member 10 can be inserted into the interior of the cup and be moved around the screw shank while the outer edge of the tubular member 10 is seated on the upper edge of the cup during the wrapping operation.

Considering now more particularly the showing of FIGS. 9 and 10 of the drawings, it will be noted that the cup 35 has a tubularly shaped wall 36 which is integral with a bottom wall 37 provided with a central opening 38 of a diameter only slightly greater than the outside diameter of the threaded shank 32 of the terminal screw. The side wall 36 of the cup is cut away to provide a slot 39 that extends the depth of such wall and is open at its upper end. The width of the slot 39 at its lower end is slightly greater than the outside diameter of the largest conductor that would be used with such cups. The sides of the slot 39 taper or flare outwardly upwardly to facilitate the insertion of the conductor

into such slot. It will be observed in FIG. 9 of the drawings that in assembling a conductor with a cup, the strands 40 are laid on the top of the cup alongside the threaded shank of the screw so that the inner ends of the bared strand portions extend through the slot 39 and the outer ends of the bared strand portions project beyond the opposite side of the cup, with such outer ends in uncompacted loose relation and not bunched. The tubular member 10 is then inserted over the screw head 20 and the bent tongue 11 thereof inserted inside the upper portion of the cup 35. The tubular member 10 is then manipulated to enable the tongue 11 thereof to tuck the outer ends of the bared strands 40 into the cup 35 and underneath the screw head 20. When this has been accomplished the screw is tightened down by the screwdriver 28 in the manner previously described. During such tightening of the screw the bare wire ends 40 cannot be extruded from beneath the screw head by the cup 35. Consequently, the bared strand ends can be compressed so tightly that they in effect become compacted together underneath the screw head to provide a very good terminal from both the mechanical and electrical aspects.

The cups shown in FIGS. 11-14 have the same essential features as the above described cup 35 shown in FIG. 10. The cup of FIG. 11 differs from that of FIG. 10 in that the opening for the screw shank forms part of a slot 41 formed in the bottom wall 42 of the cup. This enables the cup to be slid into position on the terminal 21, in FIGS. 8 and 9, without removing the screw.

The bottom wall 44 in the cup of FIG. 12 has been cut away at 45 to provide an enlarged opening through which the screw head can be inserted. Thus, this cup too enables it to be mounted in proper position on the terminal without disassembling the screw therefrom. Preferably the cup of FIG. 12 is provided with a radial seat 46 which is arcuately shaped in transverse section. The portions of the bare wire ends extending through the wall slot will be locked in such seat when the screw head is tightly secured down on the wrapped around portions of such wire ends.

The cup shown in FIG. 13 of the drawings has a throat-piece 47 associated with the slot 48 in the side wall 49 thereof. This throat affords a better control of the bunched strands as they are wrapped around the terminal screw. It also coacts with one of the terminal prongs which is of course fixed, to prevent the cup and wrapped wire connector from revolving around while the screwdriver is tightening the screw head in place on the bared strands.

The cup shown in FIG. 14 illustrates how a cup can be made to accomplish the principal purposes of the cup construction of FIG. 13 using the material 50 which is cut away from the wall 51 to form the slot 52. Preferably, the cut away piece or tongue 50 is turned downwardly in a curved manner, to provide, it has been found, a better arc of the bared wire ends approaching the terminal screw and therefore a stronger connection.

The aforesaid wire containing tubular cups depicted in FIGS. 10-14 may be made of any suitable material such as aluminum, insulating material, brass, copper composition, etc. It is contemplated also that the screw and the cup can themselves function as a terminal in which case the current would be caused to flow from

the head of the screw, down through the threaded shank thereof to the cup made of electrical conducting material. Terminals of this type have been found to be advantageous in electronic apparatus, especially for use on the back of the terminals for the lead wires in television sets.

FIG. 15 of the drawings, illustrates how the screwdriver may be made an integral part of the tool to facilitate the coaction of the wrapping and securing operations. In this construction the tubular member is designated 55 and its associated inclined tongue is designated 56. The inner end of the tubular member 55 is provided with a piston 57 that is slidably movable in a barrel 58. Provided on the tubular member against the outer side of the piston 57 is a ratchet wheel 59 which is normally maintained in engagement with ratchet elements 60 fixed to the associated end of the barrel by a spring 61 seated between the piston 57 and a collar 62 fixed to the other end of the barrel. The collar 62 has secured thereto one end of a screwdriver 63 which extends therefrom through the barrel 58, a central opening in the piston 57 and the bore of the tubular member 55. The outer end of the collar 62 is provided with a grooved head 63 on which is rotatably mounted the shank 64 of a handle 65.

It will be understood that in the use of the tool of FIG. 15, the user will grasp the handle 65 with the palm of one hand and press the outer end of the tubular member lightly against the wire to be wrapped on the terminal. The wrapping operation is accomplished by turning the barrel 58 with the fingers of the same hand. Since the tubular member 55 is locked to the barrel 58 through the ratchet elements under the pressure of the spring 61, such tubular member will be turned as the barrel is turned. When the bared end of the wire is fully wrapped on the terminal screw, the user exerts a greater pressure on the handle 65 sufficient to disengage the ratchet elements 59,60 and cause the piston 57 to slide upwardly in the barrel 58 against the yielding tension of the spring 61. The disengagement of the latching elements unlocks the connection between the barrel 58 and the tubular member 55 which is retracted into the barrel as the spring is compressed under the pressure applied to the handle 65. As the tubular member 55 is retracted, the screwdriver 63 is advanced into engagement with the head of the screw. Since the screwdriver is permanently secured to the barrel 58, any continued turning of the latter will cause the screwdriver to secure the screw head against the wrapped bare wire end.

What is claimed is:

1. Apparatus for wrapping the bared ends of wire conductors on screw type electrical terminals comprising a tubular member telescopically insertable over the head of a standard terminal screw and having at its outer end a projecting tongue for wrapping the bared end of a wire around the threaded shank of the screw as said tubular member is turned, said tubular member having a length greater than the range of movement of the screw head in moving from a fully retracted position to its advanced wire securing position so that such tubular member encloses such screw head throughout such range of movement, said tubular member having a substantially uniform diameter throughout said length, and means connected to said tubular member and operable to turn the latter.

2. Apparatus such as defined in claim 1, in which said tongue bends inwardly from the outer end of said tubular member toward the longitudinal axis of said tubular member, the degree of bend of said tongue being such that said tongue tends to sweep the engaged bared end of the wire closely around the screw shank as the tubular member is turned.

3. Apparatus such as defined in claim 1, in which the leading edge of said tongue in the direction of wrapping turn of said tubular member, is provided with a sharp edge capable of biting into a bared wire end when said tubular member is turned to wrap the wire.

4. Apparatus such as defined in claim 1, in which said length of said tubular member is the length of the outer portion of said member, and said member includes an inner attachment portion having a socket receiving a male connecting part of said connected means, the inner end of said socket communicating with the opening in said outer portion of the tubular member, and the largest transverse dimension of said socket being at least as large as the diameter of the opening in said outer tubular portion.

5. Apparatus as defined in claim 4, in which said connecting means includes a tubular shank having said male connecting part formed on one end portion thereof and having an open bore extending throughout its entire length, a tubular handle member mounted on the other end portion of said shank so that the bore in said tubular shank extends through said handle member, the largest transverse dimension of said shank bore being at least as large as the diameter of the opening in said outer tubular portion.

6. Apparatus as defined in claim 1, in which said connected means includes means formed to provide an open bore extending continuously throughout the entire length thereof, such bore being in communication with the opening in said length of tubular member and having its largest transverse dimension at least as large as the diameter of the opening in said length of tubular member, and a screwdriver operable to be extendable from said bore and through said length of tubular member into engagement with the slot in a screw head enclosed by the latter.

7. Apparatus as defined in claim 1, in which said tongue is inclined toward the longitudinal axis of said tubular member, and including a wire containing cup which receives said inclined tongue and into which is inserted the wire wrapped around the screw shank by said tongue, said cup having a depth sufficient to receive all the wrapped wire and the head of said screw and having a diameter in the upper screw head receiving portion thereof such that the wrapped wire cannot be extruded between the side wall of said cup and the outer periphery of the screw head as the screw head is tightened down on the wrapped wire.

8. Apparatus as defined in claim 7, in which the side wall of said cup is notched to receive the conductor therethrough and in which the bottom wall of said cup is provided with an opening to receive the threaded shank of the screw.

9. Apparatus as defined in claim 8, in which the opening in the bottom wall of said cup is a slot extending radially to and communicating with the bottom end of the notch in the side wall of said cup so that the cup may be moved transversely into position against the screw shank.

10. Apparatus as defined in claim 8, in which the opening in the bottom wall of the cup is large enough to pass the screw head therethrough and having a reduced portion to receive the screw shank.

11. Apparatus as defined in claim 8, in which the side wall of the cup provided thereon a stop member engageable with a fixed element associated with the cup to prevent rotation of the latter during the securement of the wire to the terminal.

12. Apparatus as defined in claim 11, in which said stop member is associated with the notch in the side wall of the cup and is configured to coact therewith as a guide for the wire being connected to the terminal.

13. Apparatus as defined in claim 12, in which said stop member is substantially U-shaped in transverse section.

14. Apparatus as defined in claim 12, in which said stop member is composed of the material cut out to form the notch in the side wall of the cup and inclines downwardly from the bottom wall of the cup.

10

15. Apparatus as defined in claim 6, in which said connected means comprises a barrel, a piston slidably mounted in said barrel and connected to said length of tubular member, coacting clutch elements connected to the lower end of said barrel and the upper end of said length of tubular member, means normally maintaining said piston in an advanced position with said clutch elements interengaged to lock said length of tubular member to said barrel, and operable to cause said clutch elements to unlock said length of tubular member from said barrel, and to permit said piston to be retracted in said barrel, and in which said screwdriver is permanently secured to said barrel and has a working end retracted with respect to said length of tubular member in the advanced position of said piston and advanced with respect to said length of tubular member to engage a screw head in the retracted position of said piston, and a handle revolvably mounted on the upper end of said barrel.
